UNITED STATES PATENT OFFICE.

JOHN W. PARTRIDGE, OF BOSTON, MASSACHUSETTS.

GLOVE-BUTTONER.

SPECIFICATION forming part of Letters Patent No. 230,196, dated July 20, 1880.

Application filed June 9, 1880. (No model.)

To all whom it may concern:

Be it known that I, JOHN W. PARTRIDGE, of Boston, in the county of Suffolk and State of Massachusetts, have invented a new and useful Improvement in Glove-Buttoners, of which the following is a specification.

This improvement relates to that class of glove-buttoners known as "double" glove-buttoners—*i. e.*, those having two loops adapted for buttoning purposes; and the nature and objects of the improvement are fully described below.

In the accompanying drawings, in which similar letters of reference indicate like parts, Figure 1 is a view of my improved glove-buttoner. Fig. 2 is a view of the same with the buttoning loops spread by pressing the thumb and finger upon the ball and central loop.

The glove-buttoner consists of a ball, *a*, and a single piece of wire, whose free ends are secured in said ball. This wire is bent, as shown in the drawings, to form two buttoning-loops, *b b'*, and the small central loop, *c*, all of the shape shown.

The central support, *a*, may be a ball, as shown, or it may vary somewhat from a perfectly spherical shape, but must be capable of holding securely the ends of the wire, and may be ornamented in any manner.

The central loop, *c*, may have a safety-chain attached to it.

By means of the central loop, *c*, and the crossing-wires, which, crossing at *x* and *y*,

form a diamond-shaped central opening, a most excellent spring is provided, so that when the buttoning-loops *b b'* are desired to be enlarged the thumb and finger may be placed upon the ball *a* and loop *c*, as in Fig. 2, which are thus pressed together, guided by the crossing wires, and the buttoning-loops spread to receive a large button. Of course, a small button requires little or no enlargement of the loops.

By means of the peculiar shape of this buttoner, and especially on account of the wire crossing and bracing at *x y*, great stiffness and strength are secured even in a fine wire. These are important advantages in a glove-buttoner, where it is desirable to use as fine wire as possible.

The simplicity of the device allows it to be made at slight expense.

Having thus fully described my improvement, what I claim, and desire to secure by Letters Patent, is—

The hereinbefore-described improved double glove-buttoner, constructed of a piece of wire whose free ends are secured in the ball *a* and bent, as shown and described, to form the buttoning-loops *b* and *b'*, and central elastic or spring portion, for the purposes set forth.

JOHN W. PARTRIDGE.
